END LOAD BRACE

Edwin B. Johnson, Chicago, Ill.

Original application May 1, 1942, Serial No. 441,251. Divided and this application June 16, 1943, Serial No. 491,003

11 Claims. (Cl. 105—369)

The present invention relates to an end load brace which has been adapted for use in freight cars of the box car type, and the subject matter thereof has been divided from my prior application for patent on an improvement in a Load brace, Serial No. 441,251, filed May 1, 1942, now Patent No. 2,336,869, dated December 14, 1943.

In the past it has been common practice to utilize the very conveniently located door posts of a box car for nailing the various parts of the partitions thereto particularly when the car is being loaded at one end only or at both ends individually with different merchandise.

An object of the present invention is to provide the box car with load braces which can be readily adapted for building up partitions transversely of the freight car.

Another object is to provide cooperative means disposed in substantial alignment with the door posts transversely of the car to provide a means for holding a timber intermediate the sides of the car to back up the load when one end of the car is being loaded, this timber being readily removable and replaceable without resorting to the use of nails. Heretofore, the use of upright timbers in the center portion of the car, by fastening the same with nails or the like, has also been objectionable by reason of the fact that the car floor and the ceiling structure eventually had to be repaired due to the mutilation accompanying this method of building up of crating partitions.

All other objects and advantages associated with the device of this invention shall hereinafter appear in the following detailed description having reference to the accompanying drawings.

In the drawings:

Fig. 1 is a horizontal cross-section through a box car taken substantially along the line 1—1 in Fig. 2.

Fig. 2 is a vertical transverse sectional view of the box car taken substantially along the line 2—2 in Fig. 1.

Fig. 3 is an enlarged vertical sectional view taken along the line 3—3 in Fig. 2.

Fig. 4 is a horizontal sectional view taken along the line 4—4 in Fig. 3, and

Fig. 5 is a plan view of the well or bottom unit per se which is adapted for holding the lower end of the central timber in the car.

Referring now to Figs. 1 and 2 which diagrammatically illustrate the general construction of a freight car of the box car type, the car generally consists of the side walls 10 and 11, end walls 12 and 13, and the usual doors 14 and 15, the bal-

ance of the car being closed by the ceiling structure 16 and flooring 17. Adjacent the openings for the doors 14 and 15 are the door posts 18 and 19 at one side of the car and 20 and 21 at the other side of the car respectively. Some of the freight cars are lined from floor to ceiling with an inner liner that is usually built flush with the door posts, but in the car illustrated a belt lining 22 has been indicated which forms a lower car lining terminating substantially midway between the floor and the ceiling structure.

In Fig. 1 suitable partitions have been illustrated closing in the end portions of the car and determining the storage or shipping spaces A and B. The partition backing up the load at A in the box car is designated as a whole at 23 while the partition backing up the load at B in the box car is similarly designated as 24. The foregoing partitions are used when backing loads less than the whole car loads and when a full car shipment is being loaded the partitions 23 and 24 will not be used, but longitudinal partitions such as indicated in dotted lines 25 and 26 are then employed.

In order to carry out one of the objects of this invention, a plurality of clamping devices as indicated at 27 in Fig. 2 have been provided and associated with the door posts. Also, centrally of the car, suitable ceiling fixtures and floor wells have been utilized and are indicated in general at 28 and 29 respectively.

The clamping devices 27 above referred to form no part of the present application but are fully described in the above identified parent from which the present application has been divided. Reference may be had to the aforesaid parent for a full understanding of said clamping devices. The latter are employed to removably secure timbers T to the door posts as seen in Figs. 1 and 2.

It is apparent from the foregoing explanation that timbers such as T can be used and replaced at will to form a protective lining for the door posts and that they may be used for the reception of nails should that become necessary, or else they may be used as vertically disposed shoulders to hold the partition individual pieces or planks P of the partition 23 as best illustrated in Fig. 2. The common practice is to begin loading a car at the extreme end thereof progressively stacking the merchandise toward the center of the car and then inserting the partition pieces or planks P one by one as the height of the load increases. Under normal conditions the load, when relatively heavy, will only be stacked or piled high enough to be approximately level with the belt lining and

in this case the partition 23 will be substantially as shown in Fig. 2. It is obviously apparent that the partition pieces may be increased in height as shown in dotted lines in Fig. 2 in the cases where light loads prevail.

Referring now more particularly to Figs. 3, 4 and 5 which have to do with the ceiling fixtures 28 and the well members 29 which are adapted to centrally back up and steady the partition pieces or planks P intermediate their ends, the well fixture 29 is suitably nested in the car floor 17 and secured by a plurality of screws 46. This well is provided with a cover 47 which is normally closed by means of a spring-actuated latch bar 48 having its operating member flush with the car floor surfaces and the surface of the cover 47. Cover 47 is hinged by means of pins 48 oppositely disposed, the pins being locked against loosening by a spacer 49 suitably secured by means of screws 50 to the underside of the cover 47.

The well fixture 29 has its opening 51 of such proportions as to loosely receive a timber T' therein and one face of the opening 51 is provided with a retaining lip or claw 52 which is adapted to bite into the timber T' upon the insertion of a wedge W in the manner best shown in Fig. 3. By the use of the wedge, the timber T' is readily secured to the car floor without nailing of the timber to the floor and the wedge W after it has been driven in place can be suitably nailed to the timber T' as at 53 to prevent accidental retraction thereof.

The upper end of the timber T' is adapted to be received in a header 55 of the ceiling fixture 28, the header having a laterally disposed side thereof open as at 56 to allow the timber T' to enter into the pocket portion of the header. The header 55 is suitably secured to the ceiling structure by means of screws 57 or any other suitable means while a bracket 58 is connected between the header 55 and the ceiling 16 at the side of the header oppositely disposed to the pressure of the load.

Within the pocket portion of the header 55, the device includes a cap member 60 which is normally urged toward the car floor and against the upper end of inserted timber T' by suitably acting and supported springs 61. For all practical purposes the springs 61 can be of sufficient strength to hold the timber T' against movement out of the header 55, but this action of movement of the timber toward the opening 56 is readily counteracted and prevented by the wedge W acting within the well opening 51.

In order to properly guide the upper end of the timber T' underneath the cap 60 of the header 55, a suitable strap 62, which may or may not be in the form of a spring leaf, is riveted to the cap as at 63 and has a loose upturned end encircling a rod 64, the end portions of the rod 64 being vertically guided by the bearing blocks 65 for limited vertical movement which has been provided to compensate for the vertical movement of the cap 60 upon insertion and removal of timber T'. To further facilitate the placing of the timber T' into position to be clamped by the cap member 60, the upper corner 66 of the timber T' is chamfered, the lower corner 67 of the same timber likewise being chamfered to facilitate insertion into the well fixture 29.

It is to be understood that in building up a partition the planks P thereof are nailed to the oppositely disposed timbers T at the door posts to fasten them in place and they may be also nailed to the timber T' which is intermediate the timbers T to which they are nailed.

Obviously, the foregoing description relates to a preferred embodiment of the device as shown and illustrated by way of example in the accompanying drawings. It is contemplated, however, to make such changes as may be governed by the breadth and scope of the appended claims.

What I claim as new and desire to secure by Letters Patent is:

1. An end load brace for a conveyance comprising upper and lower aligned securing units for holding a partition timber in place, said units being fastened respectively to the ceiling and floor of the conveyance, and the upper unit having a pocket open at the adjacent load holding side of the conveyance through which opening the upper end of the timber may be inserted into the pocket, and the pocket having three sides for restraining lateral movements of the upper end of the timber in a direction away from the adjacent load holding side of the conveyance and in directions transversely of the conveyance, resilient downwardly urged clamp means interposed between the upper securing unit and the upper end of the timber for allowing limited endwise movement of said timber between the aligned units due to car weaving, the lower one of said securing units having wedge means interposed between a wall of said unit and lower end of the timber for holding said timber against radial displacement relative to both of said units, the wedge means of said unit being releasable to allow removal of said timber from said units.
2. An end load brace for a conveyance comprising upper and lower securing units for holding a partition timber in place, said units being fastened respectively to the ceiling and floor of the conveyance, and the ceiling unit having a pocket open at the adjacent load holding side of the conveyance through which opening the upper end of the timber may be inserted into the pocket, and said pocket having three sides for restraining lateral movements of the upper end of the timber in a direction away from said load holding side of the conveyance and in directions transversely of the conveyance, the lower one of said units providing a well for receiving the lower end of said timber and including wedge means for holding said one end of the timber against radial displacement in said well, a resilient downwardly urged clamp means carried by the upper units for engagement with the upper end of said timber, and guide means connected with said latter unit for guiding the upper end of the timber into engagement with said resilient clamp means.
3. An end load bracing device for a box car, and in combination, ceiling and floor securing units for holding a partition timber in place in said car, said units being fastened respectively to the ceiling and floor of the car, and said floor unit comprising a well for the reception of the lower end of said timber, and the ceiling unit comprising a pocket member for the reception of the other end of said timber, said pocket being open at the adjacent load holding side of the car through which opening the upper end of the timber may be inserted into the pocket member and said pocket member having three sides for restraining lateral movements of the upper end of the timber in a direction away from said open side of the pocket member and in directions transversely of the car, resilient downwardly urged clamp means carried by said ceiling unit pressing against the upper end of the timber to steady the latter, and said floor unit including a wedge means interposed between a wall of the well and the timber

for clamping said timber against radial movement within said well and acting to prevent withdrawal of said timber from within the pocket member of said ceiling unit.

4. An end load bracing device for a box car, and in combination, ceiling and floor units for holding a partition timber in place in said car, said units being fastened respectively to the ceiling and floor of the car, and said floor unit comprising a well for the reception of one end of said timber, and the ceiling unit comprising a pocket member having an opening at the adjacent load holding side of the car for the reception of the upper end of said timber, and three sides for restraining lateral movements of the upper end of the timber in a direction away from said opening and in directions transversely of the car and resilient downwardly urged clamp means mounted in said pocket member for pressing against the upper end of said timber, and said floor unit having wedge means disposed between a wall of the well and the timber to prevent radial movement of said timber within the well and to counteract movement of the upper end of the timber in the direction of the opening in said pocket member.

5. An end load brace structure for a conveyance including spaced upper and lower timber securing means for retaining timbers in vertical position between floor and ceiling within the cargo-carrying body of such conveyance to back up partition planks, said upper and lower securing means being substantially aligned and fastened respectively to the ceiling and floor of the conveyance, and each engaging one of the timbers respectively, each of said upper spaced timber securing means comprising a pocket open at the adjacent load holding side of the conveyance through which opening the upper end of a timber may be inserted into the pocket, the latter having three sides for restraining lateral movements of the upper end of a timber in a direction away from said open side and in directions transversely of the conveyance, a resilient downwardly urged inverted U-shaped clamp carried by each said pocket and guided thereby for vertical movement, said clamp being adapted to straddle the upper end of a timber and to urge the latter into abutting engagement with the opposite aligned timber securing means, and guide means connected between each said upper pocket and clamp to guide the upper end of a timber into operative holding position by the clamp.

6. An end load brace structure for a conveyance including upper and lower spaced timber securing means for retaining timbers in vertical position between floor and ceiling within the cargo carrying body of such conveyance to back up partition planks, said upper and lower securing means being substantially aligned and fastened respectively to the ceiling and floor of the conveyance and each engaging one of the timbers respectively, said upper timber securing means each comprising a pocket open at the adjacent load holding side of the conveyance and having three sides for restraining lateral movements of the upper end of the timber in a direction away from the open side of the pocket and in directions transversely of the conveyance, a resilient downwardly urged inverted U-shaped clamp carried by each said upper timber securing means and guided thereby, said clamp being adapted to straddle the upper end of a timber and to urge the latter into abutting engagement with the lower support, and guide means connected between each said upper

7. A pocket and clamp to guide the upper end of a timber into operative holding position by the clamp, each lower timber securing means comprising a walled timber receiving socket having a claw and wedge units connected with opposite walls thereof for holding a timber end within said socket.

8. An end load brace structure for a conveyance including upper and lower securing means for holding a timber in position within a cargo carrying body of said conveyance and to back up partition planks in said body, said securing means being fastened respectively to the ceiling and floor of the conveyance, and each securing means comprising a clamping unit, the upper timber securing means having a pocket open at the adjacent load holding side of the conveyance, and three sides for restraining lateral movements of the upper end of the timber in a direction away from the open side of the pocket and in directions transversely of the conveyance, a spring pressed downwardly urged inverted U-shaped clamping member mounted for vertical movement in the upper timber securing means and guided thereby to engage the timber and to bodily urge said timber into abutting relation with the lower of said timber securing means in operative plank holding position, and stabilizing means interposed between a wall of said lower securing means for engaging the lower end of said timber to prevent movement of the same in a lateral direction relative to the length of the timber.

9. An end load brace structure for a conveyance including upper and lower timber securing means for retaining a timber in vertical position between floor and ceiling within the cargo carrying body of such conveyance to back up partition planks, said securing means being substantially aligned and fastened respectively to the ceiling and floor of the conveyance, and each engaging an end of the timber, the upper one of said securing means comprising a pocket open at the adjacent load holding side of the conveyance and having three sides for restraining lateral movements of the upper end of the timber in a direction away from the open side of the pocket and in directions transversely of the conveyance, a resilient downwardly urged inverted U-shaped clamp carried by said upper timber securing means and guided thereby for vertical movement therein, said clamp being adapted to straddle the upper end of a timber and to urge the latter toward the floor into abutting engagement with the lower securing means, and guide means connected between said upper support and clamp to guide the upper end of a timber into operative holding position by the clamp.

10. An end load brace structure for a conveyance including upper and lower securing means for retaining a timber in vertical position between floor and ceiling within a cargo carrying body of such conveyance to back up partition planks, said securing means being substantially aligned and fastened respectively to the ceiling and floor of the conveyance, and each engaging an end of the timber, said upper securing means each comprising a pocket open at the adjacent load holding side of the conveyance and having three sides for restraining lateral movements of the upper end of the timber in a direction away from the open side of the pocket and in directions transversely of the conveyance, a resilient downwardly urged inverted U-shaped clamp carried by and guided by said upper securing means for vertical movement therein, said clamp being adapted to strad-

idle a timber and to urge the latter toward the floor into abutting engagement with the other support, and guide means connected between said upper securing means and clamp to guide the upper end of a timber into operative holding position by the clamp, and said lower timber securing means comprising a walled timber receiving well having claw and wedge units connected with opposite walls thereof for holding a timber within said socket.

10. An end load brace for a conveyance comprising aligned upper and lower timber securing units for holding a partition timber in place, said units being fastened respectively to the ceiling and floor of the conveyance, and the upper unit having a pocket open at the adjacent load holding side of the conveyance and having three sides for restraining lateral movements of the upper end of the timber in a direction away from said load holding side and in directions transversely of the conveyance, resilient downwardly urged clamping means carried by the upper timber securing unit and engaging the upper end of the timber for allowing limited endwise movement of said timber between the aligned units due to car weaving, and

the other of said units having a well to receive the other end of the timber, a claw in said well engaging said timber and preventing withdrawal thereof when engaged, and a removable wedging means in the well opposite the claw for forcing a timber into engagement therewith.

11. An end load brace for a conveyance comprising upper and lower aligned timber securing units, one attached to the ceiling of the conveyance and the other attached to the floor thereof, the latter having a well in which the lower end of the timber is received, the upper securing unit having an open side through which the upper end of the timber may be inserted into said unit and having three sides for restraining lateral movements of the upper end of said timber in a direction away from said open side and in directions transversely of the conveyance, clamp means for holding the lower end of the timber against withdrawal from the well, and clamp means associated with said well and bearing against a side of the timber to hold the upper end thereof seated in the upper unit.

EDWIN B. JOHNSON.
